LADDER

Victor M. Fowler, Spokane, Wash.

Application May 24, 1944, Serial No. 537,093

4 Claims. (Cl. 228—31)

This invention relates to a ladder and it is one object of the invention to provide a ladder with a brace or auxiliary leg which is carried by the side rail of the ladder and serves very effectively to prevent the ladder from tilting transversely when in use.

Another object of the invention is to provide the ladder with braces which extend from opposite sides thereof and are provided with feet at their lower ends which rest flat on the ground and serve very effectively to prevent the auxiliary legs or braces from penetrating the ground upon which they rest.

Another object of the invention is to so mount the auxiliary legs or braces that they may be firmly held extended for use and easily released and moved to retracted position where they will be held against side rails of the ladder and be out of the way.

Another object of the invention is to provide auxiliary legs adapted to be applied to side rails of a conventional form of ladder without making any changes in the structure of the ladder.

In the accompanying drawing:

Fig. 1 is a perspective view of a step ladder equipped with the improved auxiliary legs or braces.

Fig. 2 is a perspective view on an enlarged scale, showing the manner in which the upper end of a brace is connected with the side rail of a ladder.

Fig. 3 is a view of the lower end portion of the brace.

The ladder shown in Fig. 1, and indicated in general by the numeral 1, is a step ladder of conventional construction and includes the usual rear support 2, which has its upper end connected with the ladder by hinges 3 and is releasably held extended for use by break-joint braces 4. The ladder has the usual side rails 5 and steps 6, and it is to be understood that while the auxiliary legs or braces have been shown applied to a step ladder, they may with equal facility, be applied to straight ladders of the single or extension type.

The auxiliary legs or braces 1 may be formed of wood or other suitable material and one is carried by each side rail of the ladder. The auxiliary legs are of duplicate construction and each has its upper end portion gradually reduced in thickness to form a feathered end portion 8 having a recess 9 formed in its outer side face. A shoe 10, formed of metal, is carried by the upper end of the auxiliary leg and has inner and outer leaves 11 and 12 united at their upper ends to form a tongue 13 which is curved longitudinally and pro-

jects upwardly from the leg. The outer leaf 12 fits within the recess 9 where it is secured by a J-bolt 14 which passes through the leg and also through the inner leaf with the end of its bill or hook 15 engaged in a socket 16 formed in the leaf 11 when the nut 17 of the bolt is tightened. By having the end of the bill or hook engaged in the recess 16, the hook will be prevented from turning out of the position shown in Fig. 2, and in which position it extends longitudinally of the leg. At the lower end of the inner leaf said leaf is bent to form a lip 18 carrying a hook 19 by means of which the leg is held in extended position.

15 A plate 20 is secured against the outer side face of each side rail by screws 21 and has its lower end bent to form a lip or keeper 22 having an opening 23 therein to receive the bill of hook 19. The upper end portion of the plate is slit longitudinally to form a tongue which is bent outwardly and downwardly to form a lip or hook 24 under which the tongue 13 engages and is frictionally gripped when the leg 7 is in extended position for use. A loop or eye 25 is carried by the plate 20 to loosely receive the hook of the J-bolt 14, and, referring to Fig. 2, it will be seen that when the lip or tongue 13 is disengaged from the hook 24, the auxiliary leg may be swung transversely to move its tongue 13 into or out of engagement with the hook 13. Therefore, when the tongue is out of engagement with the hook, the auxiliary leg may be moved to a position flat against the outer side face of the companion side rail 5 of the ladder and secured by a resilient clip 26. When the auxiliary legs are flat against the side rails of the ladder they will be out of the way and the ladder may be used as a ladder of conventional construction.

40 In order to prevent the lower ends of the auxiliary legs from penetrating the ground upon which they rest, there have been provided feet 27 which are connected with the auxiliary legs by hinges 28. The leaves of the hinges carry loops 29 and 30, and a hook 31 is loosely carried by the loop 29 for movement into and out of engagement with the loop 30. When the hook is engaged with loop 30, the foot will be firmly held in lowered position, in which position it projects outwardly from the lower end of the auxiliary leg and has such engagement with the ground that the auxiliary leg will be prevented from readily penetrating the ground. When the hook is released from the loop 30, the foot may be swung 50 upwardly to folded or inoperative position close

against the outer side of the auxiliary leg, where it will be out of the way.

Having thus described the invention, what is claimed is:

1. A ladder having side rails and steps, auxiliary legs at opposite sides of the ladder, a shoe carried by the upper end of each leg and having a longitudinally curved tongue projecting upwardly therefrom, a plate mounted against the outer side face of each side rail and having a tongue at its upper end bent outwardly and downwardly to form a hook, a loop carried by and projecting outwardly from each side plate, a J-bolt for securing each shoe to the companion leg having its bill loosely engaged through the companion loop of the companion plate to mount the leg for movement from inoperative position close against the outer side of the companion rail to extended position in which the tongue fits under the companion hook in binding engagement therewith, and a hook carried by said shoe for removably engaging through an eye of the plate and holding the auxiliary leg extended.

2. A ladder having side rails and steps, bracing legs for said ladder at opposite sides thereof, plates carried by said side rails and having upper ends formed with tongues bent outwardly and downwardly to form hooks and lower ends bent outwardly to form keepers having openings therein, a loop extending outwardly from each plate in spaced relation to its upper and lower ends, a shoe for the upper end of each leg having inner and outer leaves straddling the leg and extending longitudinally thereof, said shoe having its upper end formed with a tongue projecting upwardly from the leg and curved longitudinally, a J-bolt passing through the leg and the inner and outer leaves of the shoe and having its bill loosely engaged through the loop of the companion plate to loosely mount the leg for movement from inoperative position close against the ladder to extended position in which

the tongue of its shoe engages under the hook of the plate, the lower end of the inner leaf of the shoe being bent to form a lip, and a hook loosely carried by said lip for engaging through the keeper of the companion plate and holding the leg extended.

3. A ladder having side rails, auxiliary bracing legs at opposite sides of said ladder, plates carried by the side rails and each having an outwardly and downwardly extending hook at its upper end and an outstanding keeper at its lower end, a loop extending outwardly from each plate intermediate its ends, a shoe for the upper end of each leg having an upwardly extending tongue at its upper end for engaging under the hook of the companion plate when the leg is extended for use, fasteners securing said shoe to said legs and loosely engaged through said loops to mount the legs for movement into and out of position for use and a hook loosely connected with the lower end of the shoe for engaging the keeper of the companion plate and releasably holding the auxiliary leg in its extended position.

4. A ladder having side rails, auxiliary bracing legs at opposite sides of said ladder, mounting members carried by the side rails, each of said mounting members including a hook and a keeper and a loop between the same, a shoe for each leg having an upwardly extending tongue for engaging under the hook of the companion plate when the leg is in extended position, a fastener for securing the shoe to the leg having a hooked portion projecting from the inner side of the leg and loosely engaged through the loop of the companion plate to mount the leg for movement from a position close against the ladder to extended position, and a hook carried by the shoe for detachably engaging the companion keeper and releasably holding the leg extended.

VICTOR M. FOWLER.
